UNITED STATES PATENT OFFICE.

VICTOR E. RUMBARGER, OF DAYTON, OHIO.

TRAVELING ELECTRIC SIGN.

1,194,879.

Specification of Letters Patent. Patented Aug. 15, 1916.

Application filed November 16, 1911. Serial No. 680,597.

To all whom it may concern:

Be it known that I, VICTOR E. RUMBARGER, a citizen of the United States, residing at Dayton, in the county of Montgomery and State of Ohio, have invented certain new and useful Improvements in Traveling Electric Signs, of which the following is a specification, reference being had therein to the accompanying drawing.

10 This invention relates to traveling electric signs and the object of the invention is to produce a brilliantly illuminated sign which can be transported through the streets of the city, or elsewhere, without interfering with the traffic and which can be combined with a delivery vehicle without monopolizing space which would be valuable for other purposes.

15 It is also an object of the invention to produce a sign of this character which will be of pleasing appearance when not illuminated and to place the illumination under the control of the driver of the vehicle, thus providing the vehicle with an attractive sign 20 during the day and a brilliantly illuminated sign at night.

25 In the accompanying drawings, Figure 1 is a side elevation of a delivery wagon showing my sign applied thereto; and Fig. 2 is 30 a diagrammatic view of the circuit.

35 In these drawings I have illustrated one embodiment of the invention and have shown the sign as comprising suitable letters or emblems formed or outlined by electric lamps. In the particular sign here illustrated the letters are formed by a series of apertures 1 in a metal plate 2, which forms the body or background of the sign. Back of each aperture in this plate is mounted an 40 incandescent electric lamp, 10, which, when illuminated, will be visible through the aperture and when not illuminated will be practically invisible, thereby leaving the surface of the plate smooth and unobstructed 45 to receive such decoration or lettering as may be desirable.

The sign may be supported on any suitable vehicle. As here shown I have mounted it on the frame or body 3 of a delivery 50 wagon provided with the usual running gear, comprising ground wheels 4 and having at the front the usual foot board 5. This vehicle may be driven by any suitable power or drawn by horses. This is immaterial to the carrying out of the invention,

although the sign is particularly adapted to power driven vehicles.

The electric lamps of the sign are connected with a source of electric current which may be any of the several known 60 types. In the present instance I have shown the source of current as comprising a storage battery 6 supported from the frame or body of the vehicle in a position where it will not monopolize space which can be used 65 for carrying goods, or for any other purpose, and have connected this battery by means of suitable conductors 7 and 8 with the sign, the current being distributed to the individual lamps by suitable wiring which 70 it is not necessary to here illustrate as it is of an ordinary character. Preferably, the lamps are under the control of the driver of the vehicle, and to this end I have interposed in one of the conductors, 7, a suitable switch 75 9 and have arranged the same adjacent to the driver's seat so that it can be readily manipulated by him. In the present instance the switch is mounted on the foot board so that the driver can operate the 80 same with his foot without interfering with his other duties.

It will be apparent from the foregoing description that I have provided a traveling sign which can be combined with delivery 85 wagons or other vehicles and when moved through the streets will not only present a pleasing appearance but will attract much attention; further, that I have so constructed the sign and mounted the same that 90 it will not in any way interfere with the ordinary use of the vehicle and will not monopolize space which might be used for other purposes.

95 While I have shown and described one embodiment of my invention this has been chosen for the purpose of illustration only and I wish it to be understood that I do not desire to be limited to the details of construction shown and described, for obvious 100 modifications within the scope of the appended claim will occur to a person skilled in the art.

Having thus fully described my invention, what I claim as new and desire to secure by 105 Letters Patent, is:—

In a traveling electric sign, a vehicle comprising a top, a bottom, and a driver's seat, a plurality of electric lamps carried by the side of said top arranged to form a char- 110

acter or design, a source of electrical energy carried by said vehicle below the bottom thereof, an electrical connection between said source of electrical energy and said 5 lamps, and a controlling device for said connection arranged adjacent to said driver's seat.

In testimony whereof, I affix my signature in presence of two witnesses.

VICTOR E. RUMBARGER.
